MEANS FOR ABRADING SHOE LEATHER

Fred Stuckler, Paterson, N. J.

Application July 16, 1947, Serial No. 761,266

4 Claims. (Cl. 69—1)

1

The invention relates to means for abrading shoe leather, as for the purpose of preparing and roughening sole and heel leather of shoes for the application thereto of additional leather by means of adhesives.

The present invention contemplates a novel means for abrading shoe leather said means being in the form of a strip of material, such as thick fabric, leather, plastic, or fibre, having leather abrading teeth extending from the surface thereof, said strip being constructed so that it may be detachably mounted and adjustably held on a conventional split wheel such as is usually found in shoe repair shops.

A particular feature of the present invention is the manner in which the leather roughening teeth are attached to the strip. The invention contemplates a strip of suitable material, arranged to be detachably mounted and adjustably held upon the periphery of a common split wheel, said strip having a number of staples passed from one side of said strip to the other side thereof, the bridges of the staples being flat against one side of said strip and the shanks of the staples protruding through the strip and extending beyond the other side thereof, and being sharpened to produce leather abrading teeth. In a preferred construction the staples are arranged in staggered parallel rows so that a great number of teeth may be presented upon the abrading side of the strip without causing the bridges of the various staples to overlap one another and so add to the general thickness of the assembly.

The present invention further contemplates the provision of such a leather roughening and preparing means which may be used not only to abrade the surface of leather but also to cut it into suitable shape.

The present invention further contemplates the provision of such a strip of material the length of which may be easily adjusted to accommodate the strip to the peripheries of various wheels of slightly varying diameter. Further the invention contemplates means for tightening slack within the strip caused by use and fatigue of the material of construction.

The present invention also contemplates the provision of a modified means for adjustably locking the strip to the periphery of a split wheel.

These, other and further objects and advantages of the present invention will be clear from the following description and from the drawing, in which:

Fig. 1 shows in elevation a common split wheel which is opened and upon which is mounted a strip embodying the present invention.

2

Fig. 2 shows a single staple in rectilinear perspective.

Fig. 3 shows a transverse section through the strip on the line 3—3 of Fig. 5, which is here presumed to be made of a heavy fabric, the three foremost staples being in section, and illustrates the arrangement of staples in a preferred construction.

Fig. 4 shows a part of the strip near one edge thereof, and shows the side of the strip which is applied to the periphery of a split wheel.

Fig. 5 is a perspective view of part of the assembly of Fig. 1 near the split thereof which is to the left in the last named figure.

Fig. 6 is an edge view of part of the strip, showing the arrangement of staples in a preferred construction. This preferred construction is the same with respect to Figs. 3, 4 and 6.

Fig. 7 is a perspective view of part of the assembly of Fig. 1 near the split thereof which is to the right in the last named figure.

Fig. 8 is a perspective view of that end of the strip to the right of the split in Fig. 1, and in Fig. 8 the strip and means for locking it to the split wheel are seen from beneath, or outwardly from the center of the loop formed when the strip is bent upon itself to fit the periphery of the wheel.

Fig. 9 is a perspective view of a modification of the fastening tongue illustrated in Fig. 5.

Essentially the invention consists in an abrading strip arranged to be detachably mounted on and adjustably held on the periphery of a split wheel, and in means for mounting the strip thereon and for varying the effective length of said strip with respect to said periphery and for tightening the strip against slack. Thus, I shall first describe the construction of the strip as an abrading means, and, thereafter, take up the means whereby it is suitably applied to the wheel for use.

In Fig. 1 the strip 1 is seen to be approximately equal to the circumference of the related wheel in length so that it may be looped around the periphery of the wheel and locked to the wheel, 45 within the split thereof. In the drawing I have designated the wheel as 2, a peripheral pad such as is commonly provided on such wheels as a matress to support an abrading strip by the reference numeral 3; the fixed portion of the wheel by 4, and the portion movable with respect to the shaft by 5; and the shaft by 6.

In the preferred construction shown the teeth for abrading leather are actually the sharpened shanks of staples, of which one is shown separately in perspective in Fig. 2; as all such staples are identical I have designated any staple 1, and

the shanks of any staple 8, 8, and the bridge of any staple 9.

Fig. 4 which shows that side of the strip which is applied to the wheel 2 next the peripheral pad 3, is illustrative of a short length of said strip near an edge thereof, and indicates a preferred arrangement or pattern of staples. In Fig. 4 only the bridges 9 of the various staples are seen, which bridges are parallel to the axis of rotation of the shaft 6; the shanks 8, 8, of each staple extend away from the viewer to and beyond the other side of the strip 1.

It will be noticed in Fig. 4 that the staples are provided in rows parallel to the edge of the strip; and that the rows are provided in staggered pairs so that a great number of teeth may be provided, yet ample area is provided for the various staple bridges which are not required to overlap one another and thereby add to the thickness of the strip.

Fig. 6 is a side view showing the edge of a short length of the strip, and the staple arrangement is clearly seen in that the shanks are continued through the strip, for purposes of illustration, by dotted lines.

A transverse section of the strip is seen in Fig. 3 where for purposes of illustration the staples are presumed to pass through the strip at ninety degrees thereto, and the section is taken on a plane presumed to pass through the centers of the nearer staples.

However, in actual practice, the sharpened ends of the shanks of the various staples are preferably all bent in a uniform direction, specifically the direction of rotation of the wheel.

In Fig. 1, I show only a few of the shanks 8 of the various staples, to either side of the split of the wheel; and only a few near the ends of the strip 1 are shown in Figs. 5 and 7. Of course the rows of staples are continuous all around the loop of the strip.

The ends of the shanks of the staples may be sharpened so as to present scarifying tines in the direction of rotation of the wheel; such sharpening may be conveniently effected when the staples are cut, prior to their application to the strip; and, also, of course, the ends of the staples may be sharpened by grinding after being applied to the strip.

At the end of the strip 1, I provide a member 10, which is seen in Figs. 1 and 5 to be a piece of sheet material, preferably metal, provided on the inner surface of the strip and near the end thereof and folded over the edges of the strip and pressed securely thereagainst to form a grip. A tongue 11 of the member 10 extends beyond the end of the strip 1 and, in Figs. 1 and 5, is shown to be bent inwardly (i. e., with respect to the center of the loop of the strip) at about ninety degrees to a tangent of the loop. If desired, the member 10 may be modified, as illustrated in Fig. 9, by securing the tongue 11a thereto by means of the hinge 11b. I provide slots 12, 13 and 14 in the tongues 11 and 11a as shown in Fig. 5 and Fig. 9. On the portion 4 of the wheel and on the surface thereof facing the split, two studs 15 and 16 are provided and which enter the slots 12 and 14 respectively, as shown.

At the other end of the strip 1, I provide a member 17, which is seen in Figs. 1 and 7 to be a piece of sheet material, preferably metal provided on the inner surface of the strip and near the end thereof and folded over the edges of the strip and pressed securely thereagainst similarly to member 10 to form a grip. The inner surface

of member 17 is seen in Fig. 8. On the inner surface I provide a plurality of slots 18. A member 19, serving as a link, and operatively similar to the tongue 11 of member 10 is shown in Fig. 8 in perspective. The member 19 is provided with three slots 20, 21 and 22, disposed as are the slots 12, 13 and 14 in tongue 11. On the portion of the wheel that is movable with respect to the shaft i. e., portion 5, and on the surface thereof facing the split, a stud 23 is provided for suturing the slot 21 of the member 19, as shown in Fig. 7.

It will be understood that the ends of the strip 1 are secured in any satisfactory manner to the members 10 and 17 in the vicinity of their open ends.

The studs 15, 16 and 23 are pins conventionally provided on split wheels of the type illustrated and found in shoe repair or shoe manufacturing plants and which pins have formerly been used to nail thereon a strip of abrasive material.

The portion 4 and the portion 5 of the wheel, on the surface of each facing the split, are respectively provided with recesses 24, 25 and 26, the first named recess being arranged to accommodate the stud 23 when the wheel is closed, and the last named recess being arranged to accommodate the studs 15 and 16 when the wheel is closed. Also when the wheel is closed, the slots 13, on tongue 11 and 25 and 26 on member 19, are arranged to accommodate, respectively, studs 23, and 15 and 16.

The member 19 is provided with a lug 27, arranged to be received into any slot 18 of member 17.

In mounting the strip upon wheel, the portion 4 and 5 thereof are separated as shown in Fig. 1; the strip is looped about the periphery of the wheel, and the tongue 11 properly applied over the studs 15 and 16, as shown in Fig. 5; the strip is drawn tightly around the periphery of the wheel, and member 19 being applied over stud 23, as shown in Fig. 7, the end of the strip provided with member 17 is brought against the lug 27 of member 19 until the lug is received in one of the slots 18 appropriate to the tension desired; and the wheel is then closed by means usually provided in such wheels, and locked.

Preferably the tongue 11 is not sharply turned inwardly from the rest of the member 10, so that a slight shoulder is provided and presented into the split of the wheel, as shown in Fig. 5. This shoulder provides an abutment on which the member 17 may rest, thus making a tight abutment when the split wheel is closed.

It would be quite practicable to end the strip farther back from the bend than shown in Fig. 5, so that the other end thereof might overlap slightly when the wheel is closed without increasing the effective diameter of the wheel at the junction of the strip. It will be seen that if, with wear, the effective link of the strip becomes somewhat longer, the end thereof having the member 17 attached thereto may be cut, as with a hacksaw, so that the effective length of the strip is made less, and a new slot or plurality of slots 18 are ordinarily brought into engagement with the lug 27 of the member 19. It will be of course understood that the slots 18 and the lug 27 of the member 19 also constitute a means for adjusting the abrasive strip 1 to slightly different diameter split wheels.

The operation of the means described as an abrader for leather is obvious. Also it will be

obvious that the tines provided by the shanks of the various staples may be repeatedly sharpened.

To sum up, since a flat wire is used in the practice of my invention instead of the round wire that is used with the tools of the prior art, grooves are cut into the abraded leather by the roughening tool of the present invention. The fibres of the leather are raised above the leather surface at the sides of the grooves. The cement is imbedded in the grooves and the combination of cement, grooves and raised fibres provide a locking effect that is not accomplished with any of the roughening tools of the prior art. The leather is cemented together in a manner superior to that heretofore accomplished.

Further, the diamond cut or saw tooth cutting edges of the present invention does not tear the leather, permitting my roughening tool to be lightly held against the leather with any degree of applied force. With tools in the prior art, the leather was pulled against the tool, oftentimes resulting in tearing it, which is eliminated by my tool because of the flat saw tooth or diamond shape construction, which I utilize.

I have shown only one embodiment of the present invention; but it will be understood that modifications within the scope of the invention are self-suggestive. The strip 1 may be conveniently made of a number of materials; heavy fabric, leather, plastic and fibre have been suggested, but other materials may serve.

I claim:

1. A roughening tool for the working of leather mounted on the periphery of a split wheel having a pair of sections hinged together at one end of the sections, the other ends of said sections being separable whereby the separable ends of the sections may be brought into abutment and locked together, a first one of said hinged sections having a pair of spaced pins extending outwardly from the separable end thereof, a single pin extending outwardly from the separable end of the second section, said single pin positioned between said pair of pins upon bringing the separable ends of the sections into abutment, said roughening tool comprising an abrading strip removably mounted on the periphery of the split wheel, a first member upturned at the sides thereof and overlapping the edges of the strip and secured thereto at one end thereof, a tongue extending radially down from the member upon mounting the strip on the wheel, said tongue having three spaced elongated slots, two of said slots for receiving therein the two pins extending from the first section upon mounting the strip on the wheel and the third of said slots on said tongue receiving therein the pin on said second section upon bringing the separable ends of the two sections into abutment, a second member secured to the other end of the strip and upturned at the sides thereof and overlapping the edges of the strip,

said second member having a plurality of spaced slots underneath the strip, the said spaced slots on the second member being parallel to the axis of the split wheel, and an element having a lug extending therefrom and three spaced slots for receiving the pin on the second section and the pins on the first section upon bringing the two sections together, the lug on said element received in a slot of the plurality of slots in the second member upon locking the sections together with the abrading strip mounted on the periphery of the wheel.

2. A roughening tool for the working of leather and for removably mounting on the periphery of a split wheel having a pair of sections hinged together at one end of each section and being separable at the other end of each section, said separable ends to be brought together into abutment and locked, a first one of said sections having mounting means thereon at the separable end thereof, a second one of said sections having mounting means thereon at the separable end thereof, said roughening tool comprising a strip of flexible abrading material, a first member secured to the strip at one end thereof and having a tongue extending down from the member for engaging the said mounting means and securing the member on said first section, a second member secured to the other end of the strip and having a plurality of spaced slots underneath the strip, and an element for engaging the mounting means on said second section for securing the element on said second section, said element having means for selectively positioning the element in a slot in the second member to vary the effective length of the strip upon mounting the strip on the periphery of the wheel.

3. The roughening tool of claim 2, said first member having a shoulder in rear of the tongue to receive thereon the other end of said strip upon mounting the strip on the periphery of the wheel.

4. The roughening tool of claim 2, said tongue being hingedly connected to said first member.

FRED STUCKLER.
